UNITED STATES PATENT OFFICE.

FRANCIS CZERNY, OF OCEANPARK, CALIFORNIA, ASSIGNOR OF FIVE-TWELFTHS TO M. C. MCKENNEY, OF SAN BERNARDINO, CALIFORNIA, THREE-TWELFTHS TO ALFRED McRAE AND FOUR-TWELFTHS TO ALFRED ALBERT McRAE, BOTH OF OCEANPARK, CALIFORNIA.

AMUSEMENT DEVICE.

Application filed April 10, 1922. Serial No. 551,223.

To all whom it may concern:

Be it known that I, FRANCIS CZERNY, a citizen of the Republic of Bohemia, residing at Oceanpark, in the county of Los Angeles and State of California, have invented new and useful Improvements in Amusement Devices, of which the following is a specification.

This invention relates to amusement devices, and in particular the present invention is adaptable for beaches and like places where some animal, such as a monkey, may be strapped within a car built to simulate an automobile and a suitable trip arrangement provided whereby when the trip is actuated the car is caused to move down an incline and loop. The device of course proves most amusing to spectators.

The invention has for an object the provision of an amusement device which is relatively simple and inexpensive in construction.

With the above mentioned and other objects in view, the invention consists in the novel and useful provision, formation, construction, combination, association and inter-relation of parts, members and features, as illustrated in some of its embodiments in the accompanying drawings, described in the following statement, and finally pointed out in claims.

In the drawings:

Figure 1 is a side elevation of the amusement device;

Figure 2 is a top plan view of the amusement device;

Figure 3 is a fragmentary front elevation of the device;

Figure 4 is a fragmentary view of one of the cars or vehicles;

Figure 5 is a fragmentary detail of the incline showing a chain member for moving the car to the top of said incline;

Figure 6 is a fragmentary detail of the member carried by the car for engaging the chain member adapted to move the car up the incline; and

Figure 7 is a fragmentary detail of the trip mechanism for releasing the car so that the same may descend the incline for the performance of a looping operation.

Corresponding parts in all the figures

are designated by the same reference character.

With particular reference to the drawings, A designates in its entirety the amusement device, of which a is a track member, the said track member including an incline portion 1 leading to a loop portion 2, and a return incline portion 3 leading to the top 60 of a platform 4. A number of vehicles b may ride upon this track.

The purpose of the invention, as stated, is to cause a vehicle b to rapidly descend the incline 1 and loop on the portion 2, and thereafter ascend the incline 3 to the top of the platform 4. The vehicles v may simulate an automobile and some animal such as a monkey may be strapped within said vehicle. A track 5 is placed in front 70 of the loop portion 2. It is intended that spectators and others should stand in front of the wall c, as at the portion 6, and some missiles such as balls or other objects are handled by the spectators for the purpose 75 of throwing the same at targets d (see Figs. 3 and 7). When these targets are hit by the missile they are caused to assume the position indicated by the dotted lines in Figure 7 at 7, inasmuch as the target 80 which may comprise a tag shaped member hingedly connected as at 8 to a support or post 9, to actuate a trip mechanism e, the said member d and the trip mechanism being connected as by means of cords or 85 chains 10 and 10^a. The trip comprises a rod 11 carrying a collar 12, said rod projecting beneath or through a floor 13 on top of the platform 4, with an end as 14 engaged by the cord 10^a. A spring 15 is concentric 90 upon the rod 11 and acts to hold the rod in an upright position until such time as the spring is depressed by the rod moving downwardly, being actuated by a pull exerted upon the cords 10 and 10^a by the target d assuming the position shown by the dotted lines in Figure 7. It will be noted that the track a includes two spaced rail members 16 and 17 as is usual, and that the trip e is intermediate the rail members. The 100 platform 4 may have its front face portion 17 provided with a screen or foraminous portion 18, the space included between the foraminous portion, the side walls and the

back wall providing a cage for the harboring of small animals such as monkeys, which will of course attract attention. Immediately below this foraminous portion 18 there is provided a screen of fabric material 19, such as canvas, and this screen is provided with a plurality of openings 20 which lead directly to the target members *d*. Obviously, if some missile were thrown 10 toward the openings 20 the same might miss the said openings and would then bound against the screen 19. For this reason the screen is held in position at its lower edge by means of springs 21 in order to aid in 15 absorbing the force of the impact of the missile thereon. It is to be noted that a plurality of cords or chains 10 are provided one for each of the targets *d* and that said cords connect with a single intermediate 20 cord or chain 10^a which connects with the rod 11.

To properly support the track *a* with its looped portion 2, an inclined floor 22 is provided with uprights 23 for sustaining the 25 weight of the rails. Diagonal bracing members 24 may be provided as between the uprights. The looped portion is conventional and may consist of a square outer frame work 25 with supporting members 26 joined with the curved rail 2 forming the 30 loop. From the end of the loop, as 27, the rail portion 28 is slightly raised and carried upon a front platform 29, to where it joins the track portion 5 and then connects 35 with the incline 3. In order to return the cars *b* after they have made the descent and loop, suitable elevating means *f* is provided, said means including a chain member 30 intermediate the rails 16 and 17 of the 40 portion 3, with a sprocket 31 at the top of the incline and a second sprocket 32 at the bottom of the incline, there being a motor 33 in driving relation through the medium of a belt 34 with the shaft upon which the 45 sprocket 32 is mounted. One of the car members *b* is illustrated in Figure 4, and it is to be noted that the car member is provided with flanged wheels 35 adapted to ride on top of the rails 16 and 17. The 50 rails 16 and 17 include two portions, namely, a portion 36 and a second portion 37 extending beyond the portions 36. The car member, and particularly the chassis frame is provided with angled members 38, each of 55 which carries a wheel 39 adapted to bear upon the under surface of the members 37 where they extend beyond the members 36. It will thus be seen that danger of the car leaving the rails is practically eliminated, 60 and if for some unknown reason the car should fail to make the loop, any animal carried in the car would not be killed by the car dropping or leaving the rails. Each car is provided near the rear end thereof 65 with a pivoted arm *g* provided with a nose

40. This arm *g* after the car has traversed the track portion 5 and reaches the inclined portion 3, will fall under weight of gravity to a position where the nose 40 will engage some one of the links 41 of the chain 30. 70 The car body is provided with a stop 42 so that the arm *g* is limited as to its movement in one direction, and hence the car *b* will be carried up the incline until it reaches the top of the platform 4, whereupon the 75 car may move, due to the fact that the track portion, as 43, on top of the platform 4 is slightly inclined downwardly toward the incline 1. The car will then move forward until it engages the trip *e*. When the trip 80 is actuated, as before described, the car will then repeat its cycle of operations. Obviously any number of cars may be provided, and after one car has been released by the trip *e* the next car following will be engaged by the trip and held in position until 85 said trip is released, and so on.

It is obvious that an amusement device of this character is novel in its arrangement of the various parts and features, and would 90 afford much amusement to both young and old.

It is obvious that many changes, variations and modifications may be made, in 95 departure from the general description and showing of the accompanying drawings in adapting the invention to varying conditions and requirements of use and service, without departing from the true spirit of the invention. 100

Having thus disclosed my invention, I claim and desire to secure by Letters Patent:

1. An amusement device, including a track having two inclined portions and inter-connecting portions, one of said inclined 105 portions having a loop therein; a platform for supporting said inclined portions, a vehicle adapted to ride on said track-way, and means for holding said vehicle in position for descent on the inclined track-way having the loop portion; said means including a trip; there being a target member, and means connecting said target and trip, whereby when the target is moved the trip releases the vehicle. 115

2. An amusement device, including a track having two inclined portions and inter-connecting portions, one of said inclined portions having a loop therein; a platform for supporting said inclined portions, a vehicle adapted to ride on said track-way, and means for holding said vehicle in position for descent on the inclined track-way having the loop portion; said track-way including two rail members provided with 125 inwardly projecting portions; said vehicle being provided with flanged wheels adapted to ride on said track-way; further wheels being provided adapted to ride on the inwardly projecting portions of the track-way 130

for aid in preventing the vehicle from leaving the track.

3. An amusement device, including a track having two inclined portions, a vehicle adapted to ride on said track, means for holding said vehicle in position for descent on one of said inclined portions of said track; said means including a trip; there being a target member and means connecting said target member and said trip, where-

by when the target is moved the trip releases the vehicle.

In testimony whereof, I have signed my name to this specification in the presence of two subscribing witnesses.

FRANCIS CZERNY.
